SNOW REMOVAL APPARATUS

John Edward Becker, Toronto, Ontario, Canada

Application October 10, 1944, Serial No. 558,103

12 Claims. (Cl. 37—43)

1

My invention relates to improvements in snow removal apparatus and particularly to the type of apparatus in which snow is gathered into a suitable element carried upon the front of the assembly from where it is fed through a blower or impeller either for scattering over a wide area or for feeding into a snow-receiving vehicle.

The object of my invention is to provide a mechanism wherein the snow is drawn into the apparatus by a suitably positioned screw conveyor rotating about an axis longitudinally of the direction of travel of the apparatus; the snow, which is carried rearwardly by the conveyor, being fed into the housing of a snow-ejecting rotary impeller rotating about an axis transversely of the travel of the apparatus.

A further and particular object of my invention is to form my screw conveyor and its housing of substantially conical form wherein the apex portion of the housing communicates with the impeller housing, the snow entering the forward open mouth of the conical housing.

Another and important feature of the invention is to construct the screw conveyor in two parts, the forward part which first contacts and conveys the snow rearwardly being designed to run at a relatively slow speed, and a rearward part contained in the apex portion of the housing being designed to rotate at a considerably higher speed in order to compensate for the reduced snow-containing capacity in the rearward portion of the cone.

With the foregoing and other objects in view, as shall hereinafter appear, my invention consists of a snow removal apparatus constructed and arranged all as hereinafter more particularly described and illustrated in the accompanying drawings in which:

Figure 1 is a side elevational view of my apparatus.

Figure 2 is a rear end elevational view thereof.

Figure 3 is an enlarged vertical longitudinal sectional view through my apparatus.

Figure 4 is a rear elevational view of the impeller incorporated in my apparatus.

Figure 5 is a front elevational view of the apparatus to the same scale as shown in Figure 3, and

Figure 6 is a schematic side view of a truck showing my apparatus mounted thereon.

Like characters of reference indicate corresponding parts in the different views of the drawings.

My apparatus broadly consists of an open-mouthed conical casing 2 which houses the screw conveyor. The casing 2 is inclined downwardly

2

and forwardly and its axis is positioned substantially tangentially to a cylindrical casing 3, which houses the impeller. The lower forward edge of the casing 2 and bottom of the impeller casing 3 are in substantially the same horizontal plane. A central shaft 4 is contained in the casing 2 and extends from its open mouth to the rearward portion of the casing where it is supported within a bearing 5. A pair of oppositely positioned similar screw conveyor flights 6 and 7 are contained in the forward portion of the housing 2, and are mounted upon a tubular member 8 through which the forward end of the shaft 4 extends.

A bushing 9 is secured within the tube 8 in the vicinity of its forward end and is designed to receive the front end of the shaft 4 which is keyed within the bushing and held in place by a nut 10 threaded on to the shaft 4 and bearing against the face of the bushing 9. The rearward end of the tube 8 is secured to a second bushing 11 which is locked to the shaft 4. It will be seen that by this construction the conveyor flight-carrying tube 8 is firmly secured upon the forward portion of the shaft 4. The open mouth of the conical casing 2 is developed into rectangular shape and carries a spider 12, the centre 13 of which is provided with a suitable bearing recess to receive the outer end of the tube 8 and thus provide the necessary bearing support for the front end of the tube.

The rearward portion of the conical casing 2 contains a second pair of oppositely positioned conveyor flights 15 and 16, which are secured upon a tubular member 17 in which the rearward portion of the shaft 4 is contained. The forward end of the tube 17 is supported upon a ball bearing 18, the assembly of which incorporates the bushing 11. The rearward portion of the tube 17 is supported within a ball bearing 19 contained within the housing portion 14. It will thus be seen, that while the tube 17 is mounted to rotate, its rotation is independent of the rotation of the shaft 4 and its sleeve 8.

The rear end of the shaft 4 carries a bevel gear 20, and the rear end of the tube 17 carries a bevel gear 21. The bevel gears 20 and 21 mesh with two bevel gears 22 and 23 carried upon a shaft 24 contained within a suitable housing 25. The bevel gear 22 is of less diameter than its meshing gear 20 and the bevel gear 23 is of greater diameter than its meshing gear 21 so that rotation of the shaft 24 will cause the bevel gear 21 and its sleeve 17 to rotate at a higher speed than the bevel gear 20 and the shaft 4 with the consequence that the pair of

conveyor flights 15 and 16 will have a higher rotative speed than the pair of conveyor flights 6 and 7 at the mouth of the casing 2.

The rearward portion 14 of the casing 2 merges into the cylindrical housing 3 and upon reference to Figure 3 it will be clearly seen that as the snow passes rearwardly through the casing 2 it will be projected into the casing 3 through the opening 50.

The casing 3 contains an impeller 26 secured upon a transverse shaft 27. As shown in the drawings, the impeller consists of four blades 28 which extend tangentially from a hub 29. The blades are scooped in the direction of their rotation, as shown in Figure 3, and are also flared rearwardly from their centre lines, as shown in Figure 4. Upon reference to Figure 3, it will be understood that it is necessary to have the conveyor-driving sleeve and shaft contained within a suitable supporting housing 60 which lies partially within the path of rotation of the blades 28. In order that the blades 28 may pass the housing 60, the blades are formed with cut away centre portions 30 as shown in Figure 4. The cut away portions 30 are just sufficiently large enough to clear the housing 60 as the impeller rotates.

The casing 3 is formed with a snow ejection orifice 31 which lies rearwardly of the housing 60, and, upon reference to Figure 3, it will be clearly seen that as the impeller 26 rotates in the direction indicated by the arrows that the snow will be ejected in a tangential direction by the impeller blades. The scoop shape of the impeller blades, as shown in Figure 3, facilitates the steady ejection of the snow through the orifice 31, and by flaring such blades rearwardly from their centre lines, as shown in Figure 4, the snow will tend to slide from the centres of the blades to their side edges, before ejection, thus allowing the blades to carry their full complement of snow, which would not be the case if the snow only collected upon the centres of the blades. It will, of course, be understood that the width of the casing 3 is just sufficient to receive the impeller so that snow cannot readily pass between the side edges of the blades and the inner side faces of the casing 3.

The construction of my apparatus is such that it can be readily mounted upon any suitable type of vehicle, for example, one or more pieces of my apparatus may be carried upon the front end of a locomotive for clearing snow from railroad tracks, or my apparatus can be mounted upon the front of a truck, as shown in Figure 6, for clearing highways, aircraft landing fields, etc. In Figure 6, I show a truck 32 carrying a suitable frame 33 for the support of my apparatus. In order to actuate my apparatus, the truck may be designed to carry an engine 34 which is independent of the driving engine of the truck.

In the drive shown in Figures 1, 2 and 6, the shaft 24 which protrudes from the housing 25 carries a sprocket or pulley 35 which is connected by either a belt or chain 36 with a sprocket 37 carried upon a jack shaft 38 suitably mounted upon a pair of brackets 39 and 40. The shaft 38 carries a sprocket or pulley 41 connected to a sprocket or pulley 42 upon the drive shaft 43 through the medium of either a belt or chain 44. The drive shaft 43 is connected through suitable crown gears with the impeller shaft 27, such gears are not shown but are contained in the housing 45. The drive shaft 43 can be actuated in any suitable manner by the engine 34,

as, for example, by a drive shaft 46 extending along the lower portion of the frame 33 and connected to both the shaft 43 and the engine 34 by suitable sprocket and chain connections 47 and 48.

In order to direct the snow when it is ejected through the orifice 31 in the casing 3, any suitable type of swingable and adjustable conduit 49 can be attached in communication with the orifice 31. The snow passing through the conduit 49 may either be directed into an accompanying snow-receiving vehicle or truck, or, as the velocity of the snow passing through the conduit 49 is very high, the snow may be dispersed over an area adjacent to the area from which the snow is being removed.

From the foregoing description, it will be appreciated that I have devised a simple and yet very practical snow removal apparatus wherein the snow drawn in to the apparatus is propelled along an uninterrupted path, without any sharp turns, to reach the ejection orifice. While I have shown a particular embodiment of my invention, it is to be understood that I can from time to time make such changes and alterations as I may deem necessary without departing from spirit of my invention, as set out in the appended claims.

What I claim as my invention is:

1. A snow removal apparatus of the character described having in combination a snow contacting and receiving screw conveyor with its axis of rotation disposed substantially longitudinally of the direction of movement of the apparatus and a snow ejection rotary impeller positioned at the rear end of the screw conveyor and into which the snow leaving the screw conveyor is fed and having its axis of rotation disposed substantially transversely of the direction of movement of the apparatus and wherein the axis of the screw conveyor is disposed substantially tangentially to the path of rotation of the impeller.

2. A snow removal apparatus as set forth in claim 1 wherein the screw conveyor is of conical form decreasing in diameter from the snow contacting end towards the impeller and with its axis of rotation disposed substantially tangentially to the path of rotation of the impeller.

3. A snow removal apparatus as set forth in claim 1 wherein the impeller is contained in a cylindrical housing formed with a snow ejection orifice positioned in the upper portion of the housing.

4. A snow removal apparatus as set forth in claim 1 wherein the axis of the screw conveyor is disposed substantially tangentially to the path of rotation of the impeller, the conveyor extending forwardly and downwardly from the top of the impeller, and a cylindrical housing in which the impeller is contained and formed with a snow ejection orifice positioned substantially in alignment with the axis of the conveyor.

5. A snow removal apparatus of the character described comprising a conical shaped snow contacting and receiving screw conveyor with its axis disposed substantially longitudinally of the direction of movement of the apparatus, an open mouthed conical casing in which the screw conveyor is contained, a snow ejection rotary impeller into which the snow leaving the screw conveyor is fed and rotating about an axis disposed substantially transversely of the direction of movement of the apparatus, and a substantially cylindrical housing in which the impeller is contained and from the upper portion of which

the conical casing projects in a forward and downward direction.

6. A snow removal apparatus as set forth in claim 5 wherein the screw conveyor consists of two parts, the forward part which first contacts and conveys the snow rearwardly being designed to run at a relatively slow speed and the rearward part being designed to run at a higher speed, a rotating shaft extending axially of the conical casing and upon the forward portion of which the forward part of the screw conveyor is carried, a sleeve rotating independently of the shaft and surrounding its rearward portion and upon which the rearward part of the screw conveyor is carried, and means for rotating the sleeve at a higher speed than the speed of the shaft.

7. A snow removal apparatus as set forth in claim 5 wherein the screw conveyor consists of two parts, the forward part which first contacts and conveys the snow rearwardly being designed to run at a relatively slow speed and the rearward part being designed to run at a higher speed, a rotating shaft extending axially of the conical casing and upon the forward portion of which the forward part of the screw conveyor is carried, a sleeve rotating independently of the shaft and surrounding its rearward portion and upon which the rearward part of the screw conveyor is carried, means for rotating the sleeve at a higher speed than the speed of the shaft, and a plurality of blades incorporated in the impeller, the outer edges of which are cut away in order that the blades may clear the screw conveyor assembly.

8. A snow removal apparatus as set forth in claim 5 wherein the screw conveyor consists of two parts, the forward part which first contacts and conveys the snow rearwardly being designed to run at a relatively slow speed and the rearward part being designed to run at a higher speed, a rotating shaft extending axially of the conical casing and upon the forward portion of which the forward part of the screw conveyor is carried, a sleeve rotating independently of the shaft and surrounding its rearward portion and upon which the rearward part of the screw conveyor is carried, means for rotating the sleeve at a higher speed than the speed of the shaft, and a plurality of substantially V-shaped blades incorporated in the impeller with the apices of the blades leading in their direction of rotation.

9. A snow removal apparatus as set forth in claim 5 wherein the screw conveyor consists of

two parts, the forward part which first contacts and conveys the snow rearwardly being designed to run at a relatively slow speed and the rearward part being designed to run at a higher speed, a rotating shaft extending axially of the conical casing and upon the forward portion of which the forward part of the screw conveyor is carried, a sleeve rotating independently of the shaft and surrounding its rearward portion and upon which the rearward part of the screw conveyor is carried, means for rotating the sleeve at a higher speed than the speed of the shaft, and a plurality of substantially V-shaped blades incorporated in the impeller with the apices of the blades leading in their direction of rotation, the outer edges of the blades being cut away to permit the blades to clear the screw conveyor assembly.

10. A snow removal apparatus as set forth in claim 1 wherein the screw conveyor consists of a forward screw and a rearward screw in axial alignment, the forward screw which first contacts and conveys the snow rearwardly rotating at a relatively slow speed and the rearward screw rotating at a higher speed, and means for simultaneously rotating the two screw conveyors at their relative speeds.

11. A snow removal apparatus as set forth in claim 1 wherein the screw conveyor is of conical form decreasing in diameter from the snow contacting end towards the impeller, the conveyor consisting of a forward screw and a rearward screw in axial alignment, the forward screw which contacts and conveys the snow rearwardly rotating at a relatively slow speed and the rearward screw rotating at a higher speed, and means for simultaneously rotating the two screw conveyors at their relative speeds.

12. A snow removal apparatus as set forth in claim 1 wherein the screw conveyor has its axis of rotation disposed substantially tangentially to the path of rotation of the impeller and is of conical form decreasing from the snow contacting end towards the impeller, the conveyor consisting of a forward screw and a rearward screw in axial alignment, the forward screw which contacts and conveys the snow rearwardly rotating at a relatively slow speed and the rearward screw rotating at a higher speed, and means for simultaneously rotating the two screw conveyors at their relative speeds.

JOHN EDWARD BECKER.
